UNITED STATES PATENT OFFICE.

AUGUST AHLBRECHT, OF PITTSBURG, PENNSYLVANIA.

APPARATUS FOR PROPELLING VEHICLES.

No. 830,631.

Specification of Letters Patent.

Patented Sept. 11, 1906.

Application filed October 30, 1905. Serial No. 284,952.

To all whom it may concern:

Be it known that I, AUGUST AHLBRECHT, a subject of the German Emperor, residing at Pittsburgh, in the county of Allegheny and State of Pennsylvania, have invented certain new and useful Improvements in Apparatus for Propelling Vehicles; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to an improved apparatus for propelling vehicles; and it comprises a means for drawing or moving the vehicle in the desired direction, means for giving the propellers a vertical and horizontal movement; and the invention further consists in the certain details of construction and combination of parts, as will be fully described hereinafter.

20 In the accompanying drawings, Figure 1 is a side sectional elevation of my improved apparatus for propelling vehicles, the portion of which broken away being identical with that shown, said section being taken on the line $y-y$ of Fig. 3, the view being constructed 25 and arranged in accordance with my invention. Fig. 2 is a plan view of the same. Fig. 3 is an end sectional view taken on the line $x-x$ of Fig. 1. Fig. 4 is an enlarged face view 30 of the eccentric grooved wheel removed from the apparatus.

35 To put my invention into practice, and thereby provide an apparatus for propelling sleighs or other vehicles, I form from suitable material a frame having an upper 1 and lower platform 2 and arrange the same to be carried in a horizontal position upon said vehicle. Placed upon the lower platform 2 and at the front and rear of the vehicle are either one or two supplemental frames 3, only one 40 of which is shown in the drawings, a description of which, together with its connected levers and operating mechanism, will be sufficient to give a clear conception of the others and also the operation of the invention.

45 Formed in the frame 3 are slides 4, in which a reciprocating cross-head 5 is made to operate, the said head being connected by a link 6 to a vertically-placed lever 7, mounted in suitable bearings 8 and projecting upward through the top platform 1 of the frame. This lever 7 is connected to a crank 11,

50 formed on a shaft 9, by means of an intermediate link 12, in a manner that a rotatable movement of said shaft will move the cross-head 5 back along the length of the slides 4. 60 This shaft 9 is connected to a drive-shaft 17 by meshing gears 13 and 15, the said drive-shaft being mounted in bearings 10 and connected to any suitable motor or engine carried by the vehicle. Attached to the drive-shaft 65 17 is a disk 28, in one face of which is formed an eccentric groove, the one portion 29 having a greater radius than the other 30, adapted to engage with rollers 27, connected to horizontally-disposed bars 25, slidably mounted in bearings 26, and each capable of a limited horizontal movement in the direction of their length. Arranged beneath the upper platform 1 of the frame are two bell-crank 23, which are supported in bearings 23' and 70 24, which are supported in bearings 23' and 75 links 24 to the horizontal bar 25 and the lower extremities of said cranks connected by links 22 to a horizontally-placed bar 20, capable of being moved vertically in guides 80 21, forming a part of the frame 3. Loosely connected to this horizontal bar 20, by means of a head 18', is a downwardly-extending propeller-bar 18, which passes freely through the cross-head 5 and may be moved vertically 85 therein. On the other side of the drive-shaft 17 is another crank-shaft 9', operated by a gear-wheel 13' by means of an idler 14' in mesh with the gear 15 of the drive-shaft 17. This crank 11' is connected to a lever 7' and 90 9c by link 6' to a cross-head similar to that already described, the said cross-head being provided with a propeller-bar and means for operating the same from the horizontal moving bar 25' on the opposite side of the eccentric disk 28.

95 In operation power is applied to the drive-shaft 17 to give the same a rapid rotatable movement. This movement is transmitted to the cross-heads 5 through the medium of 100 the several gear-wheels, cranks 11 and 11', levers 7 and 7', and connecting-links 6 and 6' to give said heads a rapid reciprocating movement in their slides 4, the one head at the front of the vehicle being drawn back while 105 the other at the rear is moving forward. This same movement of the drive-shaft 17 transmits vertical movement in opposite relation to the propeller-bars 18, the one moving upward while the other is going down, caused 110 by the action of the rollers 27 and 27' following the eccentric path of the groove formed

in the disk 28, the said rollers moving the rods 25 and 25' to operate the bell-cranks 23, thereby forcing the propeller-bars 18 into the roadway or lift the same free. This vertical movement of the propellers 18 is timed to correspond with the reciprocating movement of the cross-heads 5 in such manner that said propeller will engage with the roadway when the cross-head at the front of the vehicle is at one end of its stroke while that at the rear is at the opposite or, in other words, said heads move toward and away from each other in unison. These propeller-bars move in rapid unison and engage with the roadway to draw the vehicle forward or by reversing the rotation of the drive-shaft 17 move the same backward.

It is obvious that various slight modifications and changes may be made in the details of construction without departing from the spirit of the invention. Therefore I do not wish to confine myself to the exact construction shown and described, but wish to claim all such modified forms as would come properly within the general scope of the invention.

Having thus described my invention, what I claim, and desire to secure by Letters Patent, is—

30 1. An apparatus for propelling vehicles,

comprising a series of vertically-disposed propeller-bars supported on the vehicle and above the roadway and means for moving said propellers vertically and horizontally in opposite relations, said means comprising a reciprocating cross-head carrying said propeller-bars and an eccentric grooved disk for moving said bars vertically within the cross-heads, whereby one series is engaged to propel the vehicle while the other is moving into position. 35

2. In an apparatus for propelling vehicles, the propeller-bars arranged in series and supported in a vertical position within reach of the roadway, means for giving the same a reciprocating movement and means comprising an eccentric grooved disk operated to give the propellers a vertical movement. 45

3. In an apparatus for propelling vehicles, the propeller-bars loosely mounted and supported in reciprocating cross-heads, said bars being moved vertically by means of an eccentric grooved disk operated by the drive-shaft and a series of connected levers, as described. 50

In testimony whereof I affix my signature in presence of two witnesses.

AUGUST AHLBRECHT.
